UNITED STATES PATENT OFFICE

SAMUEL MARCUS, OF RIVERDALE, NEW YORK, ASSIGNOR TO MARKON MANUFACTURING CO. INC., OF NEW YORK, N. Y., A CORPORATION OF NEW YORK

TONGUE AND TEETH SET FOR DOLLS AND THE LIKE

Original application filed October 4, 1927, Serial No. 223,942. Divided and this application filed August 28, 1928. Serial No. 302,551.

This invention relates to a tongue and teeth set for dolls and the like, the present application being in the nature of a division of co-pending application Serial No. 223,942, filed 5 October 4th, 1927.

An object of the present improvement is to provide a set which may be easily and cheaply manufactured and which may be readily attached in position within the mouth opening 10 of a doll head.

A further object is to provide improved means whereby the tongue and teeth parts, of different colors, are easily and cheaply provided.

15 Other objects and aims of the invention, more or less specific than those referred to above, will be in part obvious and in part pointed out in the course of the following description of the elements, combinations, 20 arrangements of parts and applications of principles constituting the invention; and the scope of protection contemplated will be indicated in the appended claims.

In the accompanying drawings which are 25 to be taken as a part of this specification, and in which I have shown merely a preferred form of embodiment of the invention:—

Fig. 1 is a front elevational view of a tongue and teeth set constructed in accordance with this invention, and

Fig. 2 is a vertical sectional view taken substantially upon the plane of line II—II of Fig. 1.

Referring to the drawings for describing 35 in detail the structure illustrated therein, the reference character L indicates a base or mouth representing portion, from the centre of which projects the tongue portion G. The teeth are indicated at H. These parts are all 40 formed from a single piece of sheet material, such as sheet metal, sheet celluloid or the like, bent or otherwise formed and having one or more tangs or other appropriate fastening devices as 1—1 extending from marginal edge 45 parts in proper localities for engaging the material of the doll head for fastening the device in position within the doll head, as more fully explained in said pending application.

50 The base or mouth portion L is preferably

cupped, in simulation of the hollow interior of the mouth of a small infant, the tongue being pressed outwardly from the mouth portion in a suitably characteristic shape and disposition.

55 It is a particular feature of the present improvement that the teeth portion H shall consist of an integral part of the same material from which the remainder of the structure is formed. In the instance illustrated the teeth forming portion consists merely of a turned over extension of a marginal part of the base or body. It may be arranged at any selected point about the margin of the base, either above or below the tongue, or it may be duplicated both above and below the tongue. It may be given any desired shape according to the artistic dictates of the designer, so as to represent any form or number of teeth in any selected relation to the tongue and mouth opening of the doll head.

60 The base and tongue portions are properly colored, for instance a reddish color to simulate the tongue and interior of a child's mouth, while the teeth are appropriately colored or made white. This coloring may be applied or effected in any appropriate manner, either before or after the shaping of the sheet material into set form, but it is 65 herein suggested that as an inexpensive and satisfactory manner of producing the desired color effect the piece of sheet material from which the set is to be formed shall be previously coated with an appropriate reddish coloring material as 2 on one surface and an appropriate whitish coloring material as 3 on its opposite surface, so that when the set is completed the turning over of the teeth forming extension will expose the whitish color upon the outer surface of the teeth portion, the piece of material having been pressed with the reddish color on its forward side constituting the tongue G and the mouth portion L.

70 75 80 85 90 95 100 While the tongue G is herein shown and described as projecting centrally from a mouth portion L from which, in turn, the teeth portion H project, it will nevertheless be understood that in so far as the teeth are concerned the portion L constitutes merely a

connecting means between the tongue and the teeth. It may in some instance be reduced in size to constitute only a connecting means between the tongue and the teeth, the presence of a mouth portion at the base of the tongue being in this case practically dispensed with.

As many changes could be made in this construction without departing from the scope of the invention as defined in the following claims, it is intended that all matter contained in the above description, or shown in the accompanying drawings, shall be interpreted as illustrative only and not in a limiting sense.

Having thus described my invention, what I claim as new and desire to secure by Letters Patent is:—

1. A tongue and teeth set for doll heads, said set comprising a base part having a portion projecting therefrom shaped to represent a tongue, the whole being formed from a single piece of sheet material of tongue color on its surface from which the tongue projects and of teeth color on its reverse surface, and a part of the base being turned over and extended toward the tongue portion to thereby expose the reverse surface and said surface being shaped to represent teeth.

2. A tongue and teeth set for doll heads and the like comprising a sheet of material of reddish color on one surface and whitish color on the reverse surface, said sheet of material being pressed and formed to provide the representation of a tongue on the first mentioned surface and to expose a part of the second mentioned surface in the form of teeth adjacent the tongue.

3. A tongue and teeth set for doll heads, said set comprising a sheet of material of tongue color on one surface and of teeth color on its opposite surface, said sheet being shaped to provide a tongue projecting from its surface of tongue color, and said sheet being bent to dispose a portion of its opposite surface facing in the same direction as the first surface shaped to represent teeth in appropriate relation to the tongue.

4. A tongue and teeth set for doll heads, said set comprising a sheet of material having means on its forward surface representing a tongue, the rear surface of the sheet being of whitish color, and the sheet having a portion bent to present said whitish color facing forwardly and being shaped to represent teeth in appropriate relation to the tongue.

5. A tongue and teeth set for doll heads, said set comprising a sheet of material of tongue color on one surface and teeth color on the other surface, said sheet of material having a portion turned over upon itself to expose the teeth color of one surface at the tongue surface, the sheet of material being shaped to represent a tongue projecting from the tongue surface and said turned over por-

tion being shaped to represent teeth in appropriate relation to the tongue portion.

6. A tongue and teeth set for doll heads and the like comprising tongue and teeth portions formed from a single integral piece of material, the tongue portion projecting forwardly from one surface of said piece of material and being of reddish color on its forward surface, at least a portion of the opposite surface of said piece of material being of whitish color and said portion being bent to present said whitish color facing forwardly, and said portion being shaped to represent teeth in appropriate relation to the tongue.

7. A tongue and teeth set for doll heads comprising a single piece of sheet material, a quantity of tongue color on one surface of said sheet of material, a quantity of teeth color on the opposite surface of said sheet of material, and said sheet of material being shaped to provide tongue and teeth from said portions respectively with the colors thereof both exposed at the same side of the sheet.

8. A tongue and teeth set for doll heads, said set comprising a sheet of material having a tongue shaped projection from the forward surface thereof, a quantity of tongue color on the forwardly facing surface of said tongue shaped projection, said sheet being bent to dispose a portion of its rear surface facing forwardly, said portion being made of teeth shape and disposed in appropriate relation to the tongue shaped portion, and a quantity of teeth color on the forwardly facing surface of said teeth shaped portion.

In testimony whereof I affix my signature.

SAMUEL MARCUS.
